UNITED STATES PATENT OFFICE.

GEORGE JACOB JUNKER, OF MOUNT VERNON, ILLINOIS.

VIOLIN.

1,043,015.

Specification of Letters Patent.

Patented Oct. 29, 1912.

Application filed September 26, 1911. Serial No. 651,339.

To all whom it may concern:

Be it known that I, GEORGE J. JUNKER, a citizen of the United States, and a resident of Mount Vernon, in the county of Jefferson and State of Illinois, have invented a new and Improved Violin, of which the following is a full, clear, and exact description.

The invention relates to stringed musical instruments of the viol type, such as violins, cellos, bass viols, etc.

The object of the invention is to provide a new and improved violin arranged to produce a rich and deep tone, to permit convenient fingering of the strings, and to maintain the strings in tune for a long period without requiring retuning.

For the purpose mentioned use is made of a hollow body having approximately parallel sides or sound boards, and means connected with the said parallel sides and the strings to cause the sides to vibrate.

A practical embodiment of the invention is represented in the accompanying drawings forming a part of this specification, in which similar characters of reference indicate corresponding parts in all the views.

Figure 1 is a side elevation of the violin; Fig. 2 is an enlarged longitudinal central section of the same; Fig. 3 is a similar view 30 of the same on the line 3-3 of Fig. 4; Fig. 4 is an enlarged cross section of the same on the line 4-4 of Fig. 2; Fig. 5 is a side elevation of the tail end of the body with the chin rest in position thereon; and Fig. 6 is 35 a cross section of the same on the line 6-6 of Fig. 5.

The hollow body A of the stringed musical instrument consists essentially of parallel sides A', A², a bottom A³, a top A⁴ and ends 40 A⁵, A⁶, of which the end A⁶ is connected with the neck B terminating in the head or scroll C, provided with the usual means for holding one end of the strings D extending over the finger-board B' and over the bridge 45 E to connect with the tail piece F attached in the usual manner to the button G secured to the end A⁵ of the hollow body A.

The legs E' of the bridge E are seated on the upper ends of two vibratory bars H and 50 I, of which the bar H is short in comparison to the bar I, and the said bar H is pivoted at its lower end on a block J, glued or otherwise fastened to the inner face of the side A' of the hollow body A, and the said 55 bar H is also pivoted on a block K, glued or otherwise fastened to the under side of the

top A⁴ of the hollow body A. The bar I is connected at its lower outwardly-bent end I' with the lower portion of the side A², and the said bar I is also attached to a block L 60 secured to the inner face of the side A² approximately opposite the block J, as will be readily understood by reference to Fig. 4, and the upper ends of the bars H and I extend unobstructedly through openings A⁷ 65 formed in the top A⁴ of the hollow body A. Now by the arrangement described the sound producer consisting of the strings D stretched over the bridge E is in contact with the vibratory bars H and I, which in turn 70 are attached to the sides A' and A², which latter form two sound boards and receive the pressure of the stretched strings D in a vertical direction so as to insure a free vibration. It will further be noticed that by attaching the short and long vibratory bars H and I to the sides A' and A² in the manner described horizontal vibration of the bridge 75 E will cause the sides A' and A² to vibrate. It has been found that the sides A' and A² 80 are caused to vibrate together but in opposite directions to each other, and that such vibration causes a smooth and pure tone of increased volume.

By providing the hollow body A with 85 parallel sides A', A² it is evident that the player can readily finger the strings D on the finger-board B' as the parallel sides do not obstruct the forward or backward movement of the hand manipulating the strings 90 D on the finger-board B'. In order to render the body A as large as possible the middle portion of the bottom A³ is bent or swelled in a downward direction, as plainly indicated in the drawings. The hollow 95 body A is preferably provided at the side A² with the usual S-shaped sound holes A⁸, shown in Figs. 1 and 3.

The tail end of the side A' is provided exteriorly with a cushion L of felt or a like 100 material and with headed pins N adapted to be engaged by slots O' formed in an attaching flange O of a plate O² extending transversely and provided on the top with an angular forwardly-extending flange O³ 105 to which is fastened a chin rest P. The plate O² is also provided at the bottom with a flange O⁴ having a downward and forward extension O⁵ for supporting the shoulder pad. The slots O' are preferably 110 enlarged at their upper ends to readily pass over the heads of the pins N when placing

the chin rest in position on the body A or removing it therefrom.

Having thus described my invention, I claim as new and desire to secure by Letters

5 Patent:

1. A stringed musical instrument of the class described, comprising a hollow body provided with an apertured top and approximately parallel sides, vibratory bars 10 attached to the inner faces of the said sides, one of the said bars being long and the other short and both extending through the openings in the top of the said body, a bridge having connection with the upper 15 ends of the said vibratory bars and strings supported by the bridge.

2. A stringed musical instrument of the class described, comprising a hollow body provided with an apertured top and approximately parallel sides, blocks attached 20 to the inner faces of the said sides, a block attached to the under side of the top of the said body, a short and a long vibratory bar, the long bar being secured at its lower 25 end to the lower portion of one of the sides of the body and to the block on the said side, and the said short bar being pivoted on the block on the other side and on the said block on the top of the body, the upper 30 ends of the said bars extending through

openings in the top of the body, a bridge having connection with the upper ends of the said vibratory bars the strings supported by the bridge.

3. A stringed musical instrument of the class described, comprising a hollow body provided with an apertured top and approximately parallel sides, blocks attached to the inner faces of the said sides, a block attached to the under side of the top of said body, a short and a long vibratory bar, the long bar being secured at its lower end to the lower portion of one of the sides of the body and to the block on the said side, and the said short bar being pivoted on the block 40 on the other side and on the said block on the top of the body, the upper ends of the said bars extending through openings in the top of the body, strings, and a bridge over which pass the strings and having its legs 45 seated on the upper ends of the said vibratory bars.

In testimony whereof I have signed my name to this specification in the presence of two subscribing witnesses.

GEORGE JACOB JUNKER.
